WELL DRILLING TOOL

John H. Howard, Huntington Park, Calif.

Application November 13, 1934, Serial No. 752,836

15 Claims. (Cl. 255—61)

This invention relates to a well tool and relates more particularly to a drilling tool for use in the rotary method of well drilling. A general object of this invention is to provide an improved well drill that is particularly rapid and efficient in its drilling action.

It has been found that well drills which operate to drill an annular cut or channel in the earth formation are much more rapid in their penetration of the formation than drills which cut cylindrical or full open bores. The first mentioned type of well drills heretofore have been of limited practicability and usefulness because the cores they leave in the wells usually have to be withdrawn at intervals or must be broken up or removed by special tools. The operations of removing the cores and breaking up the cores are expensive and time consuming.

One of the objects of the present invention is to provide a simple practical well drill that is operable to rapidly and efficiently cut a comparatively narrow channel in the earth formation and simultaneously with such action destroy or cut away the core thus formed without materially reducing the cutting speed or efficiency of the drill.

Another object of the invention is to provide a well drill of the character mentioned that includes a core destroying cutter that is operable to cut away the core by a rotary cutting action and to shatter or break up the core by a hammering or percussive action. The operation of the core destroying cutter of the drill depends to a large degree upon the character of the earth formation encountered. For example when the core destroying cutter is acting on shale formation there is little resistance to its rotation and it effectively cuts away the core by rotation, and when the cutter is acting on coarse sand formations or the like offering considerable resistance to its rotation the cutter is automatically operated to break up the core by a percussive or crushing action.

Another object of the invention is to provide a well drill of the character mentioned in which the core destroying cutter operates during the usual rotation of the drill and its operation is automatic, that is, it does not necessitate special manipulation or handling of the drilling string.

A further object of the invention is to provide a well drill of the character mentioned that includes a novel toothed or cam connection between the core destroying cutter and a spring pressed hammer member whereby the cutter is rotated when there is little resistance to its rotation and

is hammered by the spring pressed hammer member when the core or earth formation offers substantial resistance to its rotation.

A further object of the invention is to provide a well drill that is effective in drilling in earth formations of various characters.

The various objects and features of my invention will be fully understood from the following detailed description of a typical preferred form and application of my invention, throughout which description reference is made to the accompanying drawing, in which:

Fig. 1 is a longitudinal detailed sectional view of a well drill embodying the present invention illustrating the core destroying cutter in its lowermost position. Fig. 2 is a view similar to Fig. 1 illustrating the core engaging cutter in an upper position. Fig. 3 is a bottom elevation of the drill. Fig. 4 is a fragmentary side elevation of a portion of the hammer member and a portion of the stem of the core engaging cutter illustrating the teeth in positions where they are about to trip or disengage and Fig. 5 is a transverse detailed sectional view taken as indicated by line 5—5 on Fig. 1.

The well drill of the present invention includes, generally, a body 10 having means 11 at its lower end for making an annular cut in the earth formation, a shiftable and relatively rotatable inner cutter 12 for destroying or cutting away the core left by the means 11, and means 13 for governing the movement or operation of the cutter 12.

The body 10 is an elongate tubular structure for carrying the means 11 and the cutter 12 and for housing the means 13. The body 10 may be varied considerably in construction and design without departing from the spirit of the invention. In the particular case illustrated in the drawing the body 10 includes three sections, namely, an upper section 14, an intermediate section 15, and a lower section 16. The upper section 14 of the body is provided with means for connecting with a drilling string of drill pipe or the like. In the particular embodiment of the invention illustrated in the drawing this means takes the form of a tapered screw-threaded pin 17 on the upper end of the body section 14. The pin 17 has a central longitudinal opening or passage 18 for conducting circulation fluid downwardly from the drilling string to the interior of the body 10. The middle or intermediate body section 15 is threaded connected with the lower end of the upper section 14 and with the upper end of the lower section 16 being in the nature of a sub. A pin 19 or its equivalent is provided

on the lower end of the lower body section 16 to carry the cutting means 11. The three body sections 14, 15 and 16 may be of uniform external diameter and may be of substantially the same 5 internal diameter as illustrated in the drawing.

The cutting means 11 on the lower end of the body is operable to cut an annular channel in the earth formation and thus leave a core of the formation which is acted upon by the inner cutter 12. The cutting means 11 includes a tubular body or shoe 20 threaded on the pin 19. A plurality of circumferentially spaced cutting parts 21 is provided on the shoe 20. The cutting parts 21 may be in the form of substantially radial 10 blades projecting downwardly from the shoe. The cutting blades 21 project outwardly from the shoe to make a cut sufficiently large in diameter 15 to readily receive the body 10 and project inwardly to form a core C that may pass into the body section 16 with suitable clearance. When the drill is rotated and fed downwardly in the usual manner the cutting blades 21 operate to cut or form an annular channel in the earth formation and where the earth formation is hard or 20 relatively hard may leave an upstanding core C which is acted upon by the inner cutter 12.

The inner cutter 12 is provided to cut away or destroy the core C of hard or relatively hard formation or to act on the formation at the 25 center of the well bore when the drill is penetrating soft earth formations. In accordance with the invention the inner cutter 12 is arranged to shift longitudinally with respect to the body 10 and to have rotary motion relative to the 30 body. The inner cutter 12 is movable between a position where it projects below the cutting blades 21 and a position within the body section 16 where it is spaced some distance above the blades 21. The core engaging inner cutter 12 has cutting parts or blades 22 on its lower end. The cutting blades 22 are designed to be effective 35 in cutting away the core when the cutter 12 rotates with the body 10 and to shatter or break up the formation or core when the cutter 12 is hammered or acted upon by the means 13. In 40 practice there may be four blades 22 radiating from the center of the lower face of the cutter 12. The active lower edges of the blades 22 are preferably inclined upwardly and outwardly so 45 that the cutter is effective in breaking up the formation or core through a percussive or crushing action.

The inner cutter 12 is provided with a central 50 upwardly projecting shank 23. The shank 23 may be connected with the cutter 12 by a suitable threaded connection 24. The shank 23 is cylindrical or round in transverse cross section and is 55 slidable and rotatable in the central opening 25 of a web 26. The web 26 extends transversely 60 across the interior of the body section 16 and is spaced a considerable distance above the lower 65 end of the section. An enlargement or head 27 is provided on the shank 23 above the web 26 and is adapted to cooperate with the web to limit the downward movement of the cutter 12 relative to the body 10. When the head 27 is in engagement 70 with the web 26 to stop the cutter 12 in its lowermost position the blades 22 of the cutter may project beyond the blades 21 of the cutting means 11 as illustrated in Fig. 1 of the drawing. When the cutter 12 is in this position it may act on the formation at the bottom of the well bore. The shank 23 operates in the opening 25 to support 75 and guide the inner cutter 12 for rotative and longitudinal movement.

The means 13 is in the nature of a control means for the inner cutter 12 and under certain conditions of operation causes the inner cutter to turn with the body 10 to cut by a rotative action and under other operating conditions operates to impart a downward hammering to the cutter 12 whereby it shatters or breaks the formation through a percussive or crushing action. The means 13 includes a hammer member 28 shiftable longitudinally in the tubular body 10. The hammer member 28 is splined or keyed to the body to slide therein and rotate therewith. In the preferred construction the hammer member 28 has spaced longitudinal keys or splines 29 slidable in keyways 30 in the inner wall of 15 the body section 15. Open or unoccupied keyways 31 are provided in the wall of the section 15 between the keyways 30 carrying the splines 29. The open keyways 31 form fluid or circulation 20 passages in the wall of the section 15. The hammer member 28 is adapted to strike or hammer downwardly against the shank 23 and in the form of the invention illustrated in the drawing the hammer member 28 is provided in its lower 25 end with a central socket 32 adapted to receive 27. The side surface of the anvil part 30 has suitable clearance with the side wall of the socket 32. The parts are proportioned so that the upper 30 end wall 34 of the socket 32 is adapted to strike 33 the upper end of the anvil part 33 to impart a downward hammer blow to the anvil part 33 and the cutter 12 connected therewith. A port 35 is provided in the hammer member 28 to communicate with the upper end of the socket 32 to provide 35 for the free escape of fluid trapped in the socket.

A central upwardly projecting stem 36 is provided on the hammer member 28. The stem 36 extends upwardly into the body section 14 and 40 is slidable in an opening 37 in a transverse web 38 in said body section. The stem 36 slidably operating in the opening 37 guides and centers the hammer member 28 in the body. A suitable block or cap 39 may be provided on the upper end of 45 the stem 37 to limit the downward movement of the hammer member 28 when the body sections are disconnected. The cap 39 has clearance with the web 38 when the parts are assembled as illustrated in the drawing and does not operate 50 to limit the movement of the hammer member 28. In accordance with the invention the hammer member 28 is spring urged or spring actuated. A spiralled or coiled spring 40 surrounds the stem 36 and is arranged under compression between 55 the upper end of the hammer member 28 and the web 38 to normally urge the hammer member downwardly. The spring 40 urges the hammer member downwardly to cooperate with the anvil part 33 and the head 27 and thus urges the cutter 60 12 downwardly against the earth formation or core.

The means 13 includes a series of cam parts or teeth 41 on the lower end of the hammer part 28 to cooperate with complementary or meshing 65 cam-like teeth 42 on the head 27. The teeth 41 and 42 are formed to transmit rotative movement from the hammer member 28 to the inner cutter 12 when there is little resistance to rotation of the cutter 12 and operate as cams to feed 70 the hammer member 12 upwardly against the action of the spring 40 and then suddenly release or trip to allow the hammer member to impart downward blows to the cutter 12 when the cutter 12 is acting on formation which materially resists 75

its rotation. The teeth 41 of the hammer member 28 have forward faces 43 inclined downwardly and rearwardly relative to the direction of rotation of the drill during operation. The rear 5 sides or faces 44 of the teeth 41 may be axial or substantially vertical. The teeth 42 of the head 27 have axial or substantially vertical forward faces 45 and downwardly and rearwardly inclined rear faces 46, to cooperate with the correspondingly inclined faces 43 of the teeth 41. The points 10 or outer ends of the teeth 41 and 42 may be suitably flattened. The parts are related so that the ends or points of the teeth 41 and 42 have clearance with the bottoms of the notches between the 15 teeth when the face 34 is in contact with the upper end of the anvil part 33. With the parts related in this manner the teeth 41 and 42 are not subjected to excessive deforming impacts when the means 14 operates to impart hammering 20 blows to the anvil part 33.

When there is relatively little resistance to rotation of the cutter 12 the teeth 41 and 42 remain in mesh to form a rotative drive or connection between the body 10 and cutter 12. When 25 the tool is operating in an earth formation which provides appreciable resistance to rotation of the cutter 12 the cutter 12 drags or lags and the inclined faces 43 of the teeth 41 slide upwardly on the inclined surfaces 46 of the teeth 42 to 30 feed the hammer member 28 upwardly against the action of the spring 40 and thus store energy or force in the spring. Upon the ends of the teeth 41 riding or passing over the ends of the teeth 42 the hammer member 12 is allowed to 35 suddenly move downwardly with considerable force to impart a downward blow to the anvil part 33 to drive the cutter 12 into the core or earth formation. At this point it may be noted that the cooperating cam parts or teeth 41 and 42 operate to raise or move the hammer part 28 without raising the body 10 or its cutting means 11.

The invention includes means whereby the circulation fluid is discharged downwardly through the body 10 to aid in eroding the core and to 45 maintain a proper circulation in the well bore. A plurality of spaced ports 48 is provided in the web 38 to pass the fluid downwardly into the lower portion of the body section 14. The key ways 31 of the section 15 conduct the circulation 50 fluid downwardly past or around the hammer member 28 into the upper portion of the body section 16. A plurality of vertical or longitudinal ports 49 is provided in the web 26 to discharge the circulation fluid downwardly into the lower 55 end portion of the body section 16. The fluid discharging from the ports 49 effectively washes or flushes the cutter 12, and when a core C is received in the lower end of the tool, this fluid may erode or wash away the formation of the 60 core. When the drill is operating in soft earth formations the circulation fluid discharging under pressure from the ports 49 may soften and erode the formation to such an extent that the cutter 12 under the pressure of the spring 40 65 may maintain a down position such as illustrated in Fig. 1 of the drawing.

In operation the tool or drill is connected with the lower end of a drilling string of drill pipe and is rotated and fed downwardly in the well in the 70 usual manner. The blades 21 of the cutting means 11 operate to cut an annular channel in the earth formation. Circulation fluid is continuously pumped downwardly through the drilling string and discharges from the ports 49 to 75 flow from the lower end of the drill and pass

upwardly around the drill. The inner cutter or core destroying cutter 12 is yieldingly urged downwardly by the spring 40 to engage and act on the formation in the center of the well bore. When the drill is operating in earth formations 5 such as shale, which do not offer excessive resistance to rotation of the cutting parts the cutter 12 may turn with the body 10 so that its cutting blades 22 cut away the formation or core through a dragging or rotative action. The teeth 10 41 cooperating with the teeth 42 transmit rotation from the splined hammer member 28 to the stem 23 to provide for the rotation of the cutter 12. In some instances the inner cutter 12 may maintain its lowermost position illustrated in 15 Fig. 1 of the drawing while in other instances the inner cutter may be held upwardly with respect to the body 10 and operate in a position such as illustrated in Fig. 2 of the drawing. It is to be noted that the teeth 41 and 42 remain 20 in cooperation or engagement regardless of the longitudinal disposition of the inner cutter 12.

When the drill is operating in formations which offer excessive resistance to rotation of the cutting parts the inner cutter 12 may be 25 held against rotation or may lag through its engagement with the upper end of the core C or with the earth formation. When this occurs the forward inclined faces 43 of the teeth 41 shift upwardly on the faces 46 of the teeth 42 30 causing the hammer member 28 to move upwardly against the action of the spring 40. When a core C is present the cutter 12 may be in a position such as illustrated in Fig. 2 of the drawing and the spring 40 may be compressed 35 to a substantial degree. The upward feeding of the hammer member 28 due to the cooperation of the teeth 41 and 42 further increases the compression strain on the spring 40. Upon the surfaces or faces 43 of the teeth 41 moving out 40 of engagement with the faces 46 the teeth 41 snap or trip over the upper ends of the teeth 42 and thus allow the hammer member 12 to suddenly move downwardly under the action of the compressed spring 40. The teeth 41 and 42 45 are again brought into mesh during this downward movement of the hammer member. The hammer member 28 is moved downwardly with considerable force and the wall 34 of its socket 32 is brought into hammering engagement with 50 the upper end of the anvil part 33. This hammer action or blow is transmitted directly to the inner cutter 12 and the inner cutter shatters or breaks up the core C or formation. It will be apparent that downward hammering 55 blows are successively transmitted to the inner cutter 12 as long as the formation offers appreciable or excessive resistance to its rotation.

The means 13 operates to automatically impart downward hammering blows to the cutter 12 during the normal or usual rotation of the drill. The downward feeding or drilling pressures on the drill may maintain the cutting means 11 in its proper cooperation with the earth formation and the blades 21 are not raised 65 from the bottom of the bore when the hammer member 28 is moved upwardly and released to impart the hammering blows to the inner cutter 12. The operation of the core destroying inner cutter 12 is entirely automatic and the drill does 70 not have to be reciprocated to break up the core by a percussive or hammering action. The operation of the inner cutter 12 depends upon the character of the formation being penetrated and the means 13 automatically governs its opera- 75

tion. The formation of the free upstanding core C is readily shattered and broken away by the downward blows of the inner cutter 12. The cutting means 11 is rapid and efficient in operation and its speed and efficiency are not appreciably affected by the operation of the means 12. The drill of the present invention is particularly efficient and is capable of proper effective operation in earth formations of various characters.

Having described only a typical preferred form and application of my invention I do not wish to be limited or restricted to the specific forms and applications herein set forth, but wish to reserve to myself any modifications or variations that may appear to those skilled in the art or fall within the scope of the following claims.

Having described my invention, I claim:

1. A well drill including a tubular body to be 20 rigidly connected with a rotary drilling string, cutting means on the body for making an annular cut in the earth formation and leaving a core for reception in the body, an inner cutter retractible into the body as the core is formed 25 and proportioned to act only within said cut, and means operable by rotation of the body for imparting hammer blows to the inner cutter to cut the core as the body rotates.

2. A well drill including a body to be rigidly 30 connected with a drilling string and having an opening in its lower end, cutting means on the lower end of body for making an annular cut in the earth formation and leaving a core for reception by the opening, an inner cutter retractible into the body opening as the core is formed 35 and adapted to act on the core, and cam means in the body for hammering the inner cutter as the body rotates.

3. A well drill for use on a rotary drilling 40 string including, a body having an opening in its lower end, means for rigidly connecting the body with the drilling string, cutting means on the body for making an annular cut and leaving a core for reception by said opening, a cutter 45 for acting on the core and shiftable relative to the body to move into the opening as the core is formed, and cam means in the body causing the cutter to rotate with the body when there is little resistance to its rotation and for hammering the cutter when there is increased resistance 50 to its rotation.

4. A well drill for use on a rotary drilling 55 string including, a body, means for rigidly connecting the body with drilling string to be rotated thereby and moved vertically therewith, the body having an opening in its lower end, cutting means on the body for making an annular cut and leaving a core for reception by said opening, a cutter proportioned to act only within 60 the annular cut for acting on the core and shiftable relative to the body to move into the opening as the core is formed, and means urging the cutter downwardly relative to the body and operable by rotation of the drill to impart downward blows to the cutter.

5. A well drill for use on a rotary drilling 70 string including, a body, means for rigidly connecting the body with the drilling string, the body having an opening in its lower end, cutting means on the body for making an annular cut and leaving a core for reception by said opening, a cutter for acting on the core and shiftable relative to the body to move into the opening as the core is formed and received in the opening, a spring pressed member shiftable in the body 75

and rotatable therewith, and an operative cam connection between the cutter and member tending to cause the cutter to turn with the body and operable to impart downward blows to the cutter when it lags relative to the body.

6. A well drill for use on a rotary drilling string including, a body, means for rigidly connecting the body with the drilling string, the body having an opening in its lower end, cutting means on the body for making an annular cut and leaving 10 a core for reception by said opening, a cutter for acting on the core and shiftable relative to the body to move into the opening as the core is formed and received in the opening, a member shiftable in the body and rotatable therewith, yieldable means urging the member downwardly, and a rotative driving connecting between the member and cutter releasable whereby the yieldable means imparts blows to the cutter through 15 the medium of the member.

7. A well drill for use on a rotary drilling string including, a body, means for rigidly connecting the body with the drilling string, the body having an opening in its lower end, cutting means on the body for making an annular cut and leaving a 20 core for reception by said opening, a cutter for acting on the core and shiftable relative to the body to move into the opening as the core is formed, a shiftable spring pressed member in the body rotatable therewith, and parts on the 25 cutter and member for transmitting rotation from the member to the cutter and releasable whereby the member may give the cutter a downward blow.

8. A well drill for use on a rotary drilling string including, a body, means for rigidly connecting the body with the drilling string, the body having an opening in its lower end, cutting means on the body for making an annular cut and leaving a core for reception by said opening, a cutter for 40 acting on the core and shiftable relative to the body to move into the opening as the core is formed and received in the opening, a member shiftable in the body and rotatable therewith, yieldable means urging the member downwardly, 45 and a rotative driving connection between the member and cutter including, a shank on the cutter shiftable in the opening, and cooperating cams on the member and shank operable to move the member upwardly and suddenly disengage 50 when the cutter lags relative to the rotating body to allow the member to give the cutter a downward blow to cut away the core by precussion.

9. A well drill including a body to be rigidly 55 attached to a drilling string to be rotated thereby and move longitudinally therewith, the body having an opening in its lower end, cutting means on the lower end of the body adapted to make an annular cut and leave a core for reception by the opening, a reciprocable shank in the body, a cutter on the shank operable to act on the core and retractile into said opening, as the core is received in the opening, a spring pressed hammer member in the body rotatable therewith, and a torsion transmitting connection between the shank and hammer member releasable under a certain torque to cause an impact between the shank and member.

10. A well drill including a body to be rigidly 70 attached to a drilling string to be rotated thereby and to move longitudinally therewith, the body having an opening in its lower end, cutting means on the lower end of the body adapted to make an annular cut and leave a core for reception by the opening, a reciprocable shank in the body, a cutter 75

- on the shank operable to act on the core and retractible into said opening, a spring pressed hammer member in the body rotatable therewith, and parts on the hammer member and shank
5 adapted to cooperate for the transmission of torque, said parts having surfaces adapted to cooperate to force the hammer member upwardly and releasable to cause impact of the member against the shank.
- 10 11. A well drill including a body to be rigidly attached to a drilling string to be rotated thereby, the body having an opening in its lower end, cutting means on the lower end of the body adapted to make an annular cut and leave a core for reception by the opening, a reciprocable shank in the body, a cutter on the shank operable to act on the core and retractible into said opening, a spring pressed hammer member in the body rotatable therewith, and parts on the hammer
15 member and shank adapted to cooperate for the transmission of torque, said parts having surfaces adapted to cooperate to force the hammer member upwardly and releasable to cause impact of the member against the shank.
- 20 12. A well drill including a body to be rigidly attached to a drilling string to be rotated thereby, the body having an opening in its lower end, cutting means on the lower end of the body adapted to make an annular cut and leave a core for reception by the opening, a reciprocable shank in the body, a cutter on the shank operable to act on the core and retractible into said opening, an anvil part on the shank, a hammer member shiftable in the body and rotatable therewith and
25 adapted to engage the anvil part, a spring acting on the hammer member to urge the shank and cutter downwardly, and cam parts on the hammer member and shank adapted to transmit torque and operable under heavy torque to move the hammer member upwardly and then release it for downward movement to bring it into impact with the hammer member.
- 30 13. A well drill for use on a rotary drilling string including, a tubular body, means for rigidly connecting the body with the string, cutting means on the lower end of the body for making an annular cut and leaving a core for reception in the body, a cutter for destroying the core shiftable relative to the body to retract therein as the core is formed, a shank on the cutter, a hammer member in the body rotatable therewith and shiftable axially therein, the hammer member having a socket whose wall forms an impact surface for striking the shank, and cam means on the shank and member causing the member to strike the shank to actuate the cutter.
- 35 14. A well drill including a body to be rigidly attached to a drilling string to be rotated thereby and to move longitudinally therewith, the body having an opening in its lower end, cutting means on the lower end of the body adapted to make an annular cut and leave a core for reception by
